United States Patent Office

Des. 210,712

Patented Apr. 2, 1968

210,712

MATTRESS TICKING

Harry B. Olson, Maple Plain, Minn., assignor to The
Land of Nod Company, Minneapolis, Minn.

Filed Nov. 21, 1966, Ser. No. 4,748

Term of patent 14 years

(CL D92—1)

FIG. 1

FIG. 2

FIG. 3

FIG. 1 is a plan view of a mattress ticking showing my new design, the design repeats from top to bottom as shown and on both sides, the left edge matching the right and the right edge matching the left;

FIG. 2 is an enlarged fragmentary plan view of a portion of the design; and

FIG. 3 is an enlarged fragmentary view of another portion thereof.

I claim:

The ornamental design for a mattress ticking, as shown and described.
